(57) **CLAIM**

The ornamental planar loudspeaker, as shown and described.

DESCRIPTION

FIG. 1 is a front perspective view of the planar loudspeaker showing an embodiment of our new design;

FIG. 2 is a top plan view thereof;

FIG. 3 is a front elevation view thereof;

FIG. 4 is a right side elevation view thereof;

FIG. 5 is a left side elevation view thereof; and,

FIG. 6 is a bottom plan view thereof.

The broken lines shown are included for the purpose of illustrating portions of the planar loudspeaker that form no part of the claim.
